UNITED STATES PATENT OFFICE.

THOMAS R. EDDY, OF CHICAGO, ILLINOIS, ASSIGNOR OF ONE-HALF TO JACOB SILBERMAN, OF NEW YORK, N. Y.

TEMPORARY BINDER.

1,289,133.

Specification of Letters Patent. Patented Dec. 31, 1918.

Application filed February 2, 1917. Serial No. 146,122.

To all whom it may concern:

Be it known that I, THOMAS R. EDDY, a citizen of the United States, residing at 224 South Jefferson street, Chicago, in the 5 county of Cook and State of Illinois, have invented a new and useful Improvement in Temporary Binders, of which the following is a specification.

This invention relates particularly to 10 binders of that class in which the upper clamping bar is frictionally held in connection with the binding posts rising from the lower clamping bar, and more especially to the species of binders of this class in which 15 the upper clamping bar and the locking mechanism applied thereto are provided with rearwardly opening slots to facilitate the application and removal of the upper clamping bar to the binding posts.

20 The primary object is to provide such binders with an improved friction-lock which will grip the binding post with great security when the upper clamping bar is applied to the post, but which will release 25 with great facility to enable the removal of the upper clamping bar from the post to be effected.

The invention is illustrated in its preferred embodiment in the accompanying 30 drawing, in which—

Figure 1 represents a broken plan view of a binder constructed in accordance with my invention; Fig. 2, a rear elevational view of the same; Fig. 3, an inner or bottom view 35 of a lock-casing employed; Fig. 4, a broken plan view of the binder, with the lock-casing removed from the upper clamping bar, thus exposing the friction-lock devices; Fig. 5, a broken sectional view taken as indicated at line 5 of Fig. 2, showing one of 40 the friction-locks engaging a corresponding binding post; Fig. 6, a broken sectional view taken as indicated at line 6 of Fig. 5, this view showing the resilient, sliding cam-bar in the released position, that is, corresponding 45 with the position of said bar in Fig. 3; and Fig. 7, a sectional view of the lock-casing taken as indicated at line 7 of Fig. 3.

50 In the construction illustrated, A represents the lower clamping bar of a binder from which rise binding posts A'; B, the upper clamping bar of the binder, which is provided at its rear edge with slots 1 adapted to accommodate the posts A'; and C, the

improved locking device applied to the bar B.

It is usual to provide cover-sections 2, which are connected with the clamping bars A and B, by fabric 3, which is extended, as 60 a covering, about the clamping bars.

In Fig. 2, the binder is shown containing loose leaves, or sheets, D, clamped between the bars A and B.

The locking device C preferably comprises 65 a casing 4 in the form of an inverted elongated box, which is adapted to be secured to the clamping bar B, and which preferably incloses a mounting plate 4^a, which may be regarded as the bottom member of the casing 70 4, although not directly attached thereto; a pair of friction-lock devices 5, 5, which, in the illustration given, are mounted on the plate 4^a; and a resilient sliding cam-bar 6, which is disposed in the upper portion of 75 the casing 4 and actuated by means of a stud, or button, 6^a, which projects through a slot 6^b, with which the upper wall of the casing 4 is provided.

The casing 4, including the base-plate 4^a, 80 is cut by rearwardly opening slots 7, which register with the slots 1 of the upper clamping bar B, and are adapted to admit the binding posts.

Each locking device 5 comprises a pair of 85 post-gripping members, or jaws, 8, which are somewhat loosely connected with the mounting plate 4^a, by vertical studs 8^a, so that said jaw-members are capable of swinging freely in a horizontal plane and are also 90 capable of swinging somewhat in a vertical plane; a spring 9, which tends to throw the jaw-members 8 rearwardly, or to the open position indicated in Fig. 4; and a connecting plate 10 which overlies the operative 95 95 ends of the jaw-members and has stud-and-slot connection 10^a therewith, the connecting plate 10 being provided with a rearwardly opening slot 10^b which registers with the slot 7 of the mounting plate 4^a.

The pivotal portions of the jaw-members 8 rest upon the mounting plate 4^a, and the jaw-members are bowed, or bent, upwardly, so that the biting portions of the jaws are spaced some distance above the mounting 105 bar 4^a. The biting ends of the jaw-members are provided with post-engaging concavities, or recesses, 8^c, and thus afford lips 8^c which are adapted to engage the posts when the clamping bar B is moved rearwardly, so 110

that the posts will enter the slots. This action causes the jaw-members to swing to the post-gripping position shown in Figs. 5 and 6. The function of the connecting plate 10 is merely to maintain the biting ends of the jaw-members in approximately the same horizontal plane.

The sliding cam-bar 6, when moved to the right from the position shown in Fig. 6 to 10 the position shown in Figs. 1 and 2, is adapted to apply downward pressure upon the connecting plates 10, thereby increasing the biting action of the jaw-members. When an effort is made to raise the upper clamping bar B, the jaw-members tend to swing 15 downwardly, thereby increasing the biting action upon the binding posts. The cam-bar 6 is provided at its extremities with forks 11 and 12, which are adapted to embrace 20 the rear sides of the posts, thus closing the slots 7. The cam-bar is further provided with longitudinal recesses 13 adapted to accommodate the posts when the slide-bar is moved to the right from the position shown 25 in Fig. 3. The cam-bar 6 is further provided with cams, or depending projections, 14, which are adapted to ride upon the plates 10 and tend to depress the pairs of jaws when the cam-bar is in the locked position. 30 The cam-bar is a resilient member, having its extremities bent upwardly, as indicated at 15, so that when the cam-bar is moved to the right from the position shown in Fig. 6, downward pressure upon 35 the plates 10 will be exerted. The upcurved extremities of the cam-bar are adapted to slide in contact with the upper wall of the casing 4, so that suitable pressure will be exerted, tending to increase the biting action 40 of the jaws upon the binding posts and also holding the cam-bar in locked position.

It will be understood from the foregoing 45 that an initial biting action of the jaw-members is exerted when the jaw-members are swung from the position shown in Fig. 4 to the position shown in Fig. 5; that an additional biting action is exerted when the cam-bar 6 is moved to the right from the position shown in Fig. 6; and that any upward pressure upon the clamping bar B, such as might be exerted by the sheets D, or by an effort to lift the clamping bar, would increase the biting action of the jaw-members, owing to the tendency of the jaw-members to swing downward to a shorter 55 radius. It is to be observed, also, that the jaw-members have a toggle-lever action, both in their horizontal swinging movement and also in their vertical swinging movement. The mounting plate 4^a is shown as a continuous plate serving as a mounting 60 for both of the locking devices 5. Such a construction is convenient for manufacturing and assembling purposes; and in the 65 illustration given, the mounting plate 4^a is

shown connected at a central point, by a screw 16, to the upper clamping bar B. The invention is not limited to this manner of assembling the operative parts, however. The end walls of the casing 4 are provided 70 with depending clenching lugs 4^b, which, in the assembling operation, are passed through vertical slots in the clamping bar B and clenched beneath said bar, as shown in Fig. 6.

The foregoing detailed description has 75 been given for clearness of understanding only, and no unnecessary limitation should be understood therefrom, but the appended claims should be construed as broadly as permissible, in view of the prior art.

What I regard as new, and desire to secure by Letters Patent, is:

1. A device of the character set forth, comprising the combination of a bar provided with a slot, a pair of jaw-members 85 having loose vertical pivotal connections with said bar and having recessed biting ends adapted to engage a post, a spring tending to force the biting ends of said jaw-members toward the open end of said slot, a 90 slide-bar having a member adapted to project across said slot in the locking position of the device, and means whereby the slide-bar is adapted to depress said jaw-members to cause the biting ends to grip the post. 95

2. In a device of the character set forth, the combination of a bar provided with a slot to receive a post, a pair of jaw-members having loose vertical pivotal connections with said bar and having recessed biting 100 ends adapted to engage the post, a spring tending to force the biting ends of said jaw-members toward the open end of said slot, and a sliding cam-bar equipped with a slot-closing furcation and equipped also with a 105 cam tending to depress said jaw-members when the device is in the locked condition.

3. In a device of the character set forth, the combination of a lower clamping bar equipped with binding posts, an upper 110 clamping bar provided at its rear edge with slots adapted to receive said posts, a lock-casing carried by said upper clamping bar, and a pair of locking devices in said casing, each locking device including a pair of rearwardly opening opposed jaw-members 115 adapted to swing in a horizontal plane and having their biting ends elevated and adapted to be depressed to increase the gripping action, and means adapted to coact with said locking devices to depress said biting ends. 120

4. In a device of the character set forth, the combination of a lower clamping bar equipped with binding posts, an upper clamping bar provided at its rear edge with 125 slots adapted to receive said posts, a lock-casing carried by said upper clamping bar, and a pair of locking devices in said casing, each locking device including a pair of rearwardly opening opposed jaw-members 130

adapted to swing in a horizontal plane and having their biting ends elevated and adapted to be depressed to increase the gripping action, a spring tending to throw the 5 jaw-members rearwardly to the open position, and a cam-bar equipped with slot-closing furcations and with cams adapted to coact with said locking devices to exert downward pressure upon said jaw-members 10 when the cam-bar is in the locking position.

5. In a device of the character set forth, the combination of a lower clamping bar equipped with binding posts, an upper 15 clamping bar provided with rearwardly opening slots, a slotted lock-casing mounted on said upper clamping bar, a pair of pivotally mounted rearwardly opening jaw-members mounted in said casing at each slot and capable of swinging freely in a horizontal 20 plane and of having their biting ends depressed to increase the gripping action, a connecting plate uniting said jaw-members, a spring tending to throw said jaw-members to the open position when the post 25 is removed, and a resilient cam-bar provided with slot-closing furcations and with cams adapted to ride upon said connecting plates to depress said biting ends when the cam-bar is moved to the closed position.

30. 6. A device of the character set forth, comprising the combination of a lower clamping bar equipped with binding posts, an upper clamping bar provided with rearwardly opening slots, a lock-casing applied 35 to said upper clamping bar and provided with rearwardly opening slots registering with said first-named slots, a mounting plate in said casing provided with slots registering with the before-mentioned slots, 40 a pair of locking devices on said mounting plate, each locking device comprising a pair of rearwardly opening jaw-members,

pivotal connections between said jaw-members and said mounting plate permitting the jaw members to swing freely in a horizontal plane and enabling the biting ends of the jaw-members to be depressed to increase the gripping action, and a cam-bar 45 slidably connected with the upper wall of said casing and equipped with slot-closing 50 furcations and having cams adapted to coact with said locking devices to depress the biting ends of said jaw-members when the cam-bar is in the locking position.

7. In a device of the character set forth, 55 the combination of a post-gripping locking device, comprising a pair of opposed jaw members adapted to swing in a horizontal plane and to tilt in a vertical plane, a cam, and means to cause the cam to depress said 60 jaw members to grip the post.

8. In a device of the character set forth, the combination with a clamping bar, of a post-gripping locking device comprising a 65 pair of opposed jaw members pivotally supported on said clamping bar and adapted to swing initially in a horizontal plane and to tilt in a vertical plane, a plate connected between said jaw members, a cam, and means to cause said cam to bear against 70 said plate to depress the jaw members so that said jaw members grip the post.

9. A device of the character set forth, comprising the combination with a bar, of a pair of jaw members having loose vertical 75 pivotal connections with said bar and having recessed biting ends adapted to engage a post, a plate connecting the biting ends of the jaw-members, a cam, and means to cause said cam to bear against said plate to 80 depress said biting ends so that they grip the post.
